UNITED STATES PATENT OFFICE.

ANDREW C. ENNIS, OF MOUNT OLIVE, NORTH CAROLINA.

DEVICE FOR ELIMINATING VALVE NOISES FROM OVERHEAD VALVE MOTORS.

Original application filed April 7, 1921, Serial No. 459,422. Divided and this application filed August 11, 1921. Serial No. 491,546.

To all whom it may concern:

Be it known that I, ANDREW C. ENNIS, a citizen of the United States, residing at Mount Olive, in the county of Wayne and 5 State of North Carolina, have invented certain new and useful Improvements in Devices for Eliminating Valve Noises from Overhead Valve Motors; and I do declare the following to be a full, clear, and exact 10 description of the invention, such as will enable others skilled in the art to which it appertains to make and use the same.

This invention relates to an improved device for eliminating valve noises from a 15 motor having overhead valves operated from a cam shaft by means of rocker arms and push rods. One object of the invention is to provide a device for eliminating noises at the upper ends of the push rods and to prevent loss motion between the rocker arms 20 and push rods when the motor is in operation.

Another object of the invention is to so construct the attachment referred to that 25 they may be used in connection with push rods of a conventional construction and thus applied to motors already in use without making any change in the specific construction of the push rods of the motor.

Another object of the invention is to 30 provide a mechanism of the character described which will be simple in construction and easy to apply and further so constructed that it will be very effective in operation 35 and not liable to get out of place when in use.

This invention is illustrated in the accompanying drawings, wherein:

Figure 1 is a vertical sectional view 40 through a motor provided with the improved silencing mechanism.

Figure 2 is a fragmentary view showing in elevation a rocker arm and the upper end portion of a push rod with the improved 45 silencing device applied to the push rod.

Figure 3 is an enlarged sectional view through the silencing device with the upper end portion of the push rod shown in elevation.

This device is used in connection with 50 an internal combustion motor which is of a conventional construction. This motor is indicated in general by the numeral 1 and is provided with a cam shaft 2 and suitable 55 valves, one of which is indicated by the

numeral 3. This valve is provided with a stem 4 which extends upwardly through the upper end of the motor and carries an abutment 5 engaged by a spring 6 so that the valve will be yieldably held in a closed position and the upper end of the stem held in engagement with a rocker arm 7 pivotally mounted upon a standard 8. This rocker arm extends outwardly and is positioned above the upper end of the push rod or lifting rod 9 which is slidably mounted in a bearing 10 and has its lower end operatively engaging a plunger 11 and held against rotary movement independent of the plunger by a conventional clamp 12. This clamp 12 60 operates in the usual manner to prevent the plunger and push rod from having rotary movement and therefore the plunger will at all times be retained in proper engagement with the cam 13 carried by the shaft 2 and as the shaft 2 rotates, the plunger and push rod will be moved vertically. A device which is indicated in general by the numeral 14 and is specifically described in my co-pending application, filed April 7, 1921, Serial Number 459,422 has been provided so that the push rods will be prevented from having movement transversely of the plunger and therefore noise at this point will be prevented when the motor is in operation. 65

In order to permit the outer end portion of the rocker arm to be engaged with a minimum amount of noise, there has been provided a casing 20 which fits upon the upper end of the lifting rod and is provided 70 with a partition 21 formed of fibre. A plunger 22 slidably fits into the tubular casing 2 above the partition and is provided with an enlarged inner or lower end portion 23 which will prevent the plunger from 75 moving entirely out of the casing by striking against the inwardly extending flange 24 at the upper end of the casing. A socket 25 is provided in the enlarged inner or lower end portion of this plunger to receive a 80 spring 26, the spring engaging the fibre partition 21 and yieldably holding the plunger in a raised position for engaging the outer end portion of the rocker shaft. It will thus be seen that when the lifting rod 9 moves 85 upwardly and strikes the outer end of the rocker arm, the force of the blow will be taken up by the plunger and the plunger will be moved downwardly against the action of the spring. Therefore, the outer end 90

of the rocker arm can be engaged and the rocker arm moved upon its pivot without appreciable noise.

When applying this device for eliminating noises and taking up loss motion between the push rod and rocker arm, it is simply necessary to vertically adjust the push rod or cut off a portion of the upper end thereof and place the casing 20 upon the upper end of the push rod. The spring 26 will hold the plunger in engagement with the outer end of the rocker arm and therefore the rocker arm will at all times be engaged and noise will not be caused by a push rod striking a rocker arm.

I claim:

A silencing attachment for the upper end of a valve lifting rod comprising a sleeve for fitting upon a lifting rod, a plunger 20 slidably mounted in the sleeve, a partition

in the sleeve for engaging the upper end of the valve lifting rod, said partition being formed of cushioning material, said plunger being positioned above the partition and having a reduced end portion providing a shoulder, and having its lower end engageable with said partition and having its lower end portion provided with a pocket open at its lower end, the upper end portion of the sleeve being inwardly thickened to provide an inwardly extending flange tapered upwardly and limiting upward movement of the plunger through engagement of the shoulder thereof with said flange, and a spring in the pocket having its lower end engaging said partition and yieldably holding the plunger in a raised position.

In testimony whereof I have hereunto set my hand.

ANDREW C. ENNIS.
